UNITED STATES PATENT OFFICE

169,939

SEAL

Paul F. W. Henning, Chicago, Ill.

Application October 8, 1951, Serial No. 16,872

Term of patent 3½ years

(Cl. D1—8)

To all whom it may concern:

Be it known that I, Paul F. W. Henning, a citizen of the United States, residing at Chicago, in the county of Cook and State of Illinois, have invented a new, original, and ornamental Design for a Seal, of which the following is a specification, reference being had to the accompanying drawing, forming part thereof.

The figure is a plan view of a seal, showing my new design.

The seal is of conventional thickness.

The essential features of my design reside in those portions shown in full lines.

I claim:

The ornamental design for a seal, as shown and described.

PAUL F. W. HENNING.
